Fig.6

FIGURE 1 is a side elevational view of a hose nozzle showing my new design.

FIGURE 2 is a top plan view thereof.

FIGURE 3 is a side elevational view similar to FIGURE 1 but with the adjustable sleeve portion of the hose nozzle in its alternate position of use.

FIGURE 4 is a side elevational view of a modification of my new design.

FIGURE 5 is a top plan view thereof.

FIGURE 6 is a side elevational view similar to FIGURE 4 but with the adjustable sleeve portion of the hose nozzle in its alternate position of use.

The undisclosed sides are the same as sides shown in FIGURES 1 and 4.

This is a continuation-in-part of co-pending application Serial No. D-79,227 filed March 27, 1964, and now abandoned.

I claim:

The ornamental design for a hose nozzle, as shown and described.
